UNITED STATES PATENT OFFICE.

WAINWRIGHT B. GERVAIS, OF OAK PARK, ILLINOIS, ASSIGNOR TO VARIETY FIRE DOOR COMPANY, OF CHICAGO, ILLINOIS, A CORPORATION OF ILLINOIS.

VENTILATED FIRE DOOR.

1,427,282.

Specification of Letters Patent. Patented Aug. 29, 1922.

Application filed November 3, 1921. Serial No. 512,467.

To all whom it may concern:

Be it known that I, WAINWRIGHT B. GERVAIS, a citizen of the United States, and resident of Oak Park, in the county of Cook 5 and State of Illinois, have invented a certain new and useful Improvement in Ventilated Fire Doors, of which the following is a full, clear, concise, and exact description, reference being had to the accompanying drawings, forming a part of this specification.

My invention relates to metallic fire doors, partitions and the like and has particular reference to the method of construction 15 which provides for the circulation of air through the hollow portion of the metal door to prevent the collection of moisture within the door.

The expansion and contraction of the air 20 within a hollow metallic door, together with the changes in temperature to which the walls of the door are subjected, causes the collection and condensation of moisture within the door, which causes rusting of 25 the metal and deterioration of the heat insulating material.

An object of this invention is to provide 30 a door having small draft openings in the bottom and top in concealed positions, the interior construction of the door being such 35 as to permit air to circulate through the draft openings and throughout the length of the door from top to bottom or from bottom to top, as the tendency of air flow may exist.

A further object of my invention is to 40 provide means at the top of the door to prevent moisture which may collect thereon from entering the door through the draft opening.

Other objects of the invention will appear as the specification progresses.

My invention is illustrated in the accompanying drawings, in which

45 Figure 1 is a view in elevation of a door with two small portions thereof shown in section;

Figure 2 is a section on the line 2—2 of Figure 1;

50 Figure 3 is a section on the line 3—3 of Figure 1; and

Figure 4 is a section on the line 4—4 of Figure 1.

The door, with respect to which my invention is herein described, comprises front and rear plates 5 formed to simulate the

stile and rails of a paneled wood door, the said plates being suitably formed as at 6 to engage the pressed metal molding 7 and the channel frame member 8, which together 60 support the panels 9 and 10.

The inner surfaces of the stiles and rails are coated with fire-proof material 12, such as sheet asbestos, a similar material being confined between the metal surface plates 65 of the panels 9 and 10. The asbestos linings for the stiles and rails are held in place by means of spring metal plate stiffeners 13, which are normally so formed as to maintain a continuous pressure against the inner 70 surfaces of the fire-proof lining. These stiffeners are provided with openings 14 to permit the free circulation of air from one portion of the door to another.

Within the side members 5 at both the top 75 and the bottom of the door, the channel members 15 are welded, these members being provided respectively with a plurality of apertures 16 and 17 around which the metal is upset to form a dam against the 80 flow of such moisture as might collect in the channel into the hollow member of the door. A similar construction may be provided in the bottom of the door so that in practice the door may be used either end up. The 85 edges of the door may be formed of separate strips electrically welded to the members 5, or, if desired, the two sides of the door may be made of one piece and the metal folded around to complete the vertical door edges. 90

It will be observed that by the construction thus described, if the air in the door is warmer than that of the room into which the openings 16 and 17 discharge, the air within the door will be caused to circulate upwardly, thus carrying off the moisture which would otherwise be liable to condense within the door. A draft through the door may also be created by a difference in air pressure between the two rooms or compartments which the door separates. A door will usually be hung so that the upper edge of the door partakes more clearly of the air pressure within one room than that within the other, whereas, the air pressure beneath 105 the door will usually partake of a mean pressure between the pressures of the two rooms or compartments. This will cause a circulation through the door, either in an upwardly or downwardly direction, depending upon the tendency of air flow from one room to the other. All of these factors

combine to prevent the condensation of moisture within the door or to facilitate its evaporation in case, under severe conditions, condensation should take place.

5 I claim:

1. In a hollow metallic fire door, the provision of upper and lower perforate enclosing members, the perforations in the upper member being upwardly embossed to form 10 a dam around each of the perforations.

2. In a hollow metallic fire door, the provision of perforated upper and lower enclosing members and perforated metallic plate stiffeners within the door to provide air 15 circulation through the hollow portion of the door.

3. In a hollow metallic fire door, the combination with side plates forming stiles and rails of a perforated upper enclosing member 20 for the upper rail, and means to permit air to pass freely into or out of the bottom of the door.

4. In a hollow metallic fire door, the combination with a top rail of a channel 25 iron forming a top closure for said rail and

having its channel portion upward, the side plates of the rail being attached to the side members of the channel, the base of the channel being perforated to permit the circulation of air into and out of the top door 30 rail.

5. In a hollow metallic door, the combination with a top rail of a channel iron forming a top closure for said rail and having its channel portion upward, the side 35 plates of the rail being attached to the side members of the channel, the base of the channel having perforations therein surrounded by upwardly extending embostures 40 to permit the circulation of air into and out of the top door rail to prevent the passage of water from the channel into the hollow portion of the top door rail.

In witness whereof, I hereunto subscribe my name this 31st day of October, 1921. 45

WAINWRIGHT B. GERVAIS.
